UNITED STATES PATENT OFFICE

STEPHEN TREVERTON, OF CANTON, OHIO, ASSIGNOR TO CENTRAL ALLOY STEEL CORPORATION, OF MASSILLON, OHIO, A CORPORATION OF NEW YORK

OPEN-HEARTH FURNACE

Application filed September 8, 1927. Serial No. 218,233.

The invention relates to open hearth furnaces, having walls made of refractory material such as silicious brick, and the object of the invention is to provide an improved furnace construction enabling a renewable protection of these furnace walls wherever desired as by a material such as dolomite preferably applied in the loose form.

The walls of an open hearth furnace, particularly the front and back walls, if not provided with adequate renewable lining, are subject to destructive actions due to the chemical and physical condition of the melt in the furnace, which chemical and physical condition may include among other things high temperatures and a basic character of the melt, both of which have destructive effects, particularly upon the brick of the furnace walls.

Because of the above described chemical and physical conditions of the melt in the furnace, it is particularly necessary to protect the front and back walls above the metal line, and attempts have been made to provide for the protection of the walls above the metal line by sloping the walls upwardly and outwardly at an angle sufficient to enable a loose protective lining to rest on the sloping walls by reason of the normal angle of repose of the loose lining.

Such a construction of an open hearth furnace having upwardly and outwardly extended front and back walls, is difficult of attainment as compared with furnace construction including only a vertical arrangement of the walls, since it is necessary to provide angled buckstays for retaining the sloping walls or to greatly increase the quantity of brick required to build up the wall, when the brick is arranged so as to form a sloping interior and a vertical exterior.

Another objection to the use of sloping walls in an open hearth furnace lies in the fact that different lining materials may be used having different angles of repose, and a wall slope for the angle of repose for one material may not be suited to the angle of repose of another material.

The objects of the present invention include among other things the provision of an

open hearth furnace which may be made with substantially vertical walls and which may provide a protective lining for covering any or all portions of the vertical walls; and these objects are attained by the use of a construction including a bottom and one or more walls made up of a plurality of off-set and substantially vertical heights and a relatively broad, substantially horizontal ledge between the separate heights, and a protective lining supported by the bottom and the ledge and covering desired portions of the vertical walls.

Preferred embodiments of the invention are illustrated in the accompanying drawings, forming part hereof, in which—

Figure 1 is a horizontal cross section as on line 1—1, Figs. 3 and 4, of an open hearth furnace embodying the improvements of the present invention and including a back wall provided with ledge means for maintaining a protective lining;

Fig. 2, a vertical longitudinal cross section as on line 2—2, Figs. 3 and 4;

Fig. 3, a transverse vertical cross section as on line 3—3, Figs. 1 and 2;

Fig. 4, a transverse vertical cross section as on line 4—4, Figs. 1 and 2; and

Fig. 5, an enlarged, transverse vertical cross section similar to Fig. 4, illustrating a modified embodiment of the invention in an open hearth furnace having both front and back walls provided with ledge means for maintaining a protective lining.

Similar numerals refer to similar parts throughout the drawings.

The embodiment of the invention illustrated in Figs. 1 to 4 inclusive, is an application of the improvements to an open hearth furnace for providing protection to the back wall only.

The improved furnace, indicated generally at 1, includes a foundation grillage indicated at 2 and having transverse members 2' to 95 which are secured at their lower ends vertically extending front buckstays 3 and rear buckstays 3' and 3''.

Rear buckstays 3' and 3'' are located opposite front buckstays 3 and the opposite 100

buckstays are connected with each other at their upper ends as by tie rods 4.

Buckstays 3 and 3" as shown, extend upwards in a substantially vertical line throughout their entire length.

Rear buckstays 3', however, each include a substantially vertically extending lower strut 3'a and a substantially vertical upper strut 3'b outwardly offset from the lower 10 strut and being connected at its lower end with the upper end of the lower strut by a substantially horizontal ledge supporting beam 3'c. Diagonal brace 3'd is provided for connecting the outer end of the beam 3'c 15 with the lower end of the strut 3'a.

Within the structural framework thus formed, the refractory materials of the furnace are supported, and include a furnace bottom 5 preferably made of a refractory brick, and a vertically extending refractory brick front wall 6 abutting the buckstays 3, and provided with a plurality of charging 20 doors 7.

Opposite the front wall and abutting the 25 lower vertical strut 3'a of the buckstays 3', a vertically extending brick wall height 8 is provided, and abutting the off-set substantially vertical upper struts 3'b of the buckstays 3', an upper vertical brick back wall 30 height 9 is provided and connected at its lower end with the upper end of the wall 8 by a substantially horizontal ledge 10 supported by the beams 3'c.

At the upper ends of the walls 6 and 9 substantially horizontally extending bearing 35 channels 11 abutting the buckstays 3' and 3 are provided for transmitting the thrust of an arch roof 12.

Furnace ends 13 and 14 may be provided of 40 any usual construction and connected with the vertical off-set back wall height 9 as by angled vertically extending walls 15 and 15'.

A suitable furnace tap hole 16 may be located in the lower central portion of the back 45 wall 8. The grillage 2 may rest upon a foundation floor 17; while at the front of the furnace a suitably elevated charging platform 18 may be provided.

For protecting the brick furnace bottom 50 and back wall and for forming the dish-like furnace hearth, the furnace bottom 5 is renewably covered with preferably loose refractory material such as dolomite or magnesite 19, which extends up and beyond the 55 level of the ledge 10 to cover the entire inner surface of the back wall height 9, and being positively supported for that purpose by the ledge 10 which may be at or near the metal line of the furnace.

The transverse distance between the walls 8 and 6 is the normal transverse distance between the front and back walls of open hearth furnaces which have been used in the past, and in which wall 8 would extend vertically 60 to the junction with the roof arch.

For such furnaces it has been found very difficult to adequately protect the back wall without unduly cutting down the interior volume of the furnace chamber.

It is apparent that by the use of the present 70 invention, such open hearth furnaces may be modified with very little difficulty and provided with the relatively broad supporting ledge 10 and an outwardly off-set upper back wall height 9 which may be adequately protected by loose dolomite supported by the ledge 10. 75

In certain instances, the location of present external equipment prevents the protection 80 of the front wall of an open hearth furnace by the use of the aforesaid ledge and off-set vertical walls.

Where space permits or when building a new furnace, the construction illustrated in Fig. 5 may be utilized for providing adequate 85 protection for both front and back walls of the furnace.

The construction of Fig. 5 is substantially similar to the construction of Figs. 1 to 4 inclusive with the addition of an outwardly off-set upper height 6a of the front wall connected at its lower end by a substantially horizontal ledge 20 with a substantially vertical lower front wall height 6b, and supported by the buckstays 3". 90

The renewable loose dolomite lining 19 in this modification of the invention may thus be extended upwards and supported by the ledges 10 and 20 to protect both the front and back walls of the furnace. 100

The foregoing arrangement and construction of open hearth furnaces having a renewable lining is very easy and economical to apply to the modification of existing furnaces and to the construction of new furnaces, and 105 very materially reduces the maintenance cost of such furnaces.

Claims:

1. An open hearth furnace including a bottom and a wall, the wall including a plurality of off-set and substantially vertical heights and a substantially horizontal ledge between the separate heights near the normal metal line. 110

2. An open hearth furnace including a bottom and a wall, the wall including a plurality of off-set and substantially vertical heights, a substantially horizontal ledge between the separate heights near the normal metal line, and a lining material supported by the bottom and the ledge and covering portions of the vertical heights. 115

3. An open hearth furnace including a bottom and walls, each wall including a plurality of off-set and substantially vertical heights, a substantially horizontal ledge between the separate heights near the normal metal line, and a lining material supported by the bottom and the ledge and entirely covering the vertical heights. 120 125 130

4. An open hearth furnace including a bottom and a wall, the wall including a plurality of off-set heights, each of whose inner faces is substantially vertical, a substantially horizontal ledge between the off-set heights near the normal metal line, and a lining material supported by the bottom and the ledge and entirely covering the inner faces of the off-set heights.

10 In testimony whereof I affix my signature.
STEPHEN TREVERTON.
